Amasa Stone, of Johnson, State of Rhode Island

Letters Patent

The schedule referred to in these Letters Patent and making a part of the same containing a description in the words of the said Amasa Stone, him self of his improvement in power and other looms, for weaving silk, linen, cotton, woolen and other cloths, termed a taking up motion.

To all persons to whom these presents shall come,
Amasa Stone a native of Johnson in the county of Providence and state of Rhode Island in the United States of America (but at present in England engaged) sends greeting,

Be it known that I the said Amasa Stone have invented a new and useful improvement in power looms and other looms, for weaving silk, linen, cotton, woolen and other cloths, called a taking up motion, and that the following is a full and exact description of the construction and operation of the said machine or improvement, as invented or improved by me, that is to say, it consists in an adaptation of machinery or apparatus hereinafter described to be attached to such looms for the purpose of regulating the taking up of the cloth on the cloth beam, by giving to it at all times an equable motion and for connecting such taking up of the cloth with the beating up of the weft during the operation of weaving and by means of which whenever from the breaking of the weft or non delivery thereof, the cloth meets with little or no resistance by reason of a want of filling caused by the breaking or non delivery of the weft, the operation of the taking up motion although the general revolution of the loom remain in action.

But if the weft be pieced or renewed and the filling thereby supplied the action of the taking up will commence.

This my said improvement is connected and made to operate with my improvement in power looms and other looms for which the United States of America granted me a patent dated the thirtieth day of April

one thousand eight hundred and twenty nine and to which both the Specification drawing and model by me delivered into the proper office in pursuance and in support of such Letters Patent and in compliance of the laws of the United States of America. I now refer for the description therein given of the construction and action of those parts which form the connection and operation between the end of the loom and the gear beam by means of the horizontal shaft at which my present improvement and the description thereof begin. But in order to render this my last improvement apparent and to enable persons conversant with similar machinery to put it in practice I have annexed to this my Specification a drawing of the machinery or apparatus constituting my said improvement and of that part of a loom to which it is to be applied and also constructed a model thereof, to which drawing reference is now made by means of lettering thereon as follows, near the end of series, or woven on the horizontal shaft A, a ratchet wheel 10, is fixed corresponding in the number of its teeth (more or less) with the small bevel wheel fixed on the opposite end of the same shaft as described in the Specification of my former patent already referred to, this ratchet wheel 10, acts upon the end of the shorter arm of a bent lever C, suspended on a pivot or stud D, fixed in a bracket which is made fast to the side frame of the loom at E. At the reverse end that is near the extremity of the longer arm of the bent lever C, where the same approaches the cloth beam, a strap or link F, is appended uniting this end of the lever C, with the end of another bent lever G, at the opposite end of which attached by a moveable joint is a catch click or tooth, H. (This bent lever G with its catch, click or tooth H, is the ordinary taking up lever, which with its click or driver, works the ordinary ratchet wheel and train of toothed gear used for taking up or winding the cloth round the cloth beam as it is woven in the usual way and of course forms no part of my improvement.) Having now described the construction and adaptation of my improved machinery or apparatus, I proceed to show the manner in which it operates. The rotary motion given to the horizontal shaft A, in the way described in my said former Patent, Specification and model before referred to or one of them carries round with it the Patent wheel B, and the teeth of this ratchet wheel acting on the end of the shorter arm, of the bent lever C, causes that end of the bent lever to be depressed every time that a tooth of the ratchet wheel 10, passes over the end of the bent lever C, as shown by the dotted line in the drawing by this means the reverse end or long arm of the said bent

beam C, is raised and by the stop or links D, which unite this end of the beam with the end of the ordinary taking up beat beam E, gives motion to the same and thence by means of the catch or driver H, also gives motion to the ordinary train of toothed gear used for taking up and winding the cloth, round the cloth beam, as it is woven.

Therefore when the rotary motion of the horizontal shaft A is suspended owing to the breaking of the swift or wire delivering thereof, the taking up of the cloth beam although the general regulations of the loom continue in action. Having now described my improvement in power looms and other looms, for weaving silk, linen, other woolen, and other cloths, called a taking up motion together with the arrangement of parts by which the same may be carried into effect, I do hereby declare that I consider my claim of improvement or invention to consist in and extend to the connection of the said with the cloth beam, (in those looms where my former improvement already referred to is applied) and in the communication of motion from the one to the other and in the regulation of the motion of the cloth beam, by the motion of the said, by whatever combination of machinery apparatus or gearing the same may be effected. In testimony that the above is a true specification of my said improvement as above described I have hereunto set my hand the 1st day of March in the year of our Lord one thousand eight hundred and thirty five.
